US0D1023312S

(12) **United States Design Patent** (10) Patent No.: **US D1,023,312 S**
(45) Date of Patent: ** Apr. 16, 2024

(54) **HEMOSTATIC AGENT MATERIAL**

(71) Applicant: **GC CORPORATION**, Shizuoka (JP)

(72) Inventors: **Hiroaki Hata**, Tokyo (JP); **Norihiko Shishido**, Tokyo (JP); **Yurie Inaba**, Tokyo (JP)

(73) Assignee: **GC CORPORATION**, Shizuoka (JP)

(**) Term: **15 Years**

(21) Appl. No.: **35/516,703**

(22) Filed: **Mar. 18, 2022**

(80) **Hague Agreement Data**

Int. Filing Date: **Mar. 18, 2022**

Int. Reg. No.: **DM/220747**

Int. Reg. Date: **Mar. 18, 2022**

Int. Reg. Pub. Date: **Mar. 24, 2023**

(51) LOC (14) Cl. 24-02

(52) U.S. Cl.

USPC **D24/169**

(58) **Field of Classification Search**

(57) **CLAIM**

The ornamental design for a hemostatic agent material, as shown and described.

DESCRIPTION

1. Hemostatic agent material

1.1 : Perspective

1.2 : Front

1.3 : Back

1.4 : Left

1.5 : Right

1.6 : Top

1.7 : Bottom

1.1 perspective view; 1.2 front view; 1.3 back view; 1.4 left view; 1.5 right view; 1.6 top view; 1.7 bottom view; the local hemostatic agent of this design is put in a tooth extraction site after tooth extraction for hemostasis and protection of the wound surface.

1 Claim, 7 Drawing Sheets
